Primary Examiner — Angela J Lee(74) *Attorney, Agent, or Firm* — Varnum, Riddering, Schmidt & Howlett LLP(57) **CLAIM**

I claim, the ornamental power and data center, as shown and described.

DESCRIPTION

FIG. 1 is a rearview of my power and data center in accordance with the invention;

FIG. 2 is a top plan view thereof;

FIG. 3 is a left-side elevation view thereof;

FIG. 4 is a front elevation view thereof;

FIG. 5 is a right-side elevation view thereof;

FIG. 6 is a bottom view thereof;

FIG. 7 is a perspective view of my power and data center, showing my power and data center in an open configuration; and,

FIG. 8 is a further perspective view of my power and data center, showing my power and data center in a closed configuration.

The broken lines shown in the drawings represent portions of the power and data center that form no part of the claimed design.
